UNITED STATES PATENT OFFICE.

WILLIAM SCOTT, OF MEDFORD, MASSACHUSETTS.

CARBURETER.

1,270,558.

Specification of Letters Patent. Patented June 25, 1918.

Application filed July 20, 1914. Serial No. 851,956.

To all whom it may concern:

Be it known that I, WILLIAM SCOTT, a citizen of the United States, residing at Medford, in the county of Middlesex and State 5 of Massachusetts, have invented certain new and useful Improvements in Carbureters; and I do hereby declare the following to be a full, clear, and exact description of the invention, such as will enable others skilled 10 in the art to which it appertains to make and use the same.

The present invention relates to an improvement in carbureters. It is desirable that the carbureter, for supplying a mixture 15 of air and vaporized gasolene to an internal combustion engine, should deliver a homogeneous mixture. Many devices have been produced having in contemplation the production of such a homogeneous mixture of 20 gasolene and air. In many carbureters the gasolene is introduced into a stream of air at the center of the stream, and tortuous passages, obstructions, and other things have been availed of to cause an intimate 25 mixture of the gasolene and air, but in any stream of fluid the velocity of the center of the stream is greater than the velocity at a distance from the center, so the tendency 30 of the gasolene introduced into the center of the stream of air is to remain in the center of the stream.

The principal object of the present invention is to produce a carbureter in which the gasolene is introduced into a stream of 35 air at the exterior of the stream and at a distance from the center thereof so that as the stream flows on to the cylinders, the particles of vaporized gasolene, being heavier than the particles of air, tend to move 40 toward the center of the stream, as a result of which the air and the vaporized gasolene are intimately mixed and a homogeneous mixture is delivered to the cylinders. Another object of the present invention is to 45 produce a carbureter that will deliver a homogeneous mixture of gasolene and air irrespective of the amount of mixture demanded by the engine so that at all speeds of the engine the mixture will be substantially identical in composition.

Other objects of the invention are pointed out in connection with the description of the specific form of carbureter illustrated in the drawings and made the subject of 55 claims.

To the above ends the present invention

consists of the carbureter hereinafter described and particularly defined in the claims.

In the accompanying drawings illustrating the preferred form of the invention, Figure 1 is an elevation of the carbureter with a portion shown in vertical section to show the internal construction and with the parts in the positions which they occupy 60 when the carbureter is delivering a small amount of mixture suitable for idling speed; Fig. 2 is a sectional view on the line 2—2 of Fig. 1; Fig. 3 is a sectional elevation showing the parts in the positions which they 65 occupy when the carbureter is delivering its full capacity of mixture to the engine; Fig. 4 is a section on the line 4—4 of Fig. 3; Fig. 5 is an elevation of the gasolene control sleeve; Fig. 6 is an elevation of a modified form of the invention; and Fig. 7 is a 70 sectional plan on the line 7—7 of Fig. 6.

The illustrated embodiment of the invention is described as follows:—The carbureter consists of a mixing chamber 1 on the 80 side of which is mounted the float chamber 2 which delivers gasolene to the jet pipe. The float chamber 2 discharges through the opening 3 into the passageway 4 provided with a strainer 5 for removing any impurities 85 from the gasolene as it passes to the jet pipe. This passageway 4 discharges into an eduction chamber 6 to which the jet pipe 7 is connected. The mixing chamber 1 is cylindrical in form and is embraced by the 90 jet pipe 7 which leads from the eduction chamber 6 around the wall of the mixing chamber. This jet pipe is provided with five jets 11, 12, 13, 14 and 15. Each of the jets projects into a corresponding air tube 95 or inlet 21, 22, 23, 24 and 25. The air inlets are cylindrical tubes open on their outer ends and supported by the air tube ring 30 which embraces the exterior of the mixing chamber. These tubes 21, 22, 23, 24 and 25 100 register with holes 31, 32, 33, 34 and 35 in the wall of the mixing chamber 1. A convenient construction for associating the float chamber and the mixing chamber consists in providing the float chamber with an integral 105 annulus 8 through which the mixing chamber is adapted to be slipped into the position illustrated in Fig. 1, then two ears, the one on the float chamber and the other on the mixing chamber, are secured together 110 by the screw 9 which holds the parts in relative position. The gasolene jets are each

located, it will be observed, in an air tube through which the current flows into the mixing chamber at right angles to the direction of the path of motion of the stream of air passing through the mixing chamber. Inside of the mixing chamber there is provided a gasoline control sleeve 40 which has five ports corresponding each respectively to one of the air tubes. The ports in the order 10 of opening are 41, 42, 43, 44 and 45. The position at idling speed of the sleeve 40 is indicated in Fig. 1. At this time, the upper end of the port 41 registers with the inner end of the air tube 21 so that we have 15 a flow through the air tube 21 and port 41 into the mixing chamber. This port, as will be observed, is long. From bottom position to top position it is always open and affords a free and unobstructed passageway for air 20 and gasoline through the air tube 21 into the mixing chamber. The port 42 is somewhat shorter than the port 41 and its upper end is so located with relation to the air tube 22 that with the sleeve 40 in bottom 25 position the port is only partially open. The port 43 is shorter yet and the port 44 is still shorter, and the port 45 is a hole of the same size as the air tube 15. As the sleeve 40 is lifted from the position indicated 30 in Fig. 1 to the position indicated in Fig. 3, it gradually opens the several air tubes in their consecutive order until when the sleeve is lifted into its position all of the air tubes are open. At intermediate 35 positions the openings are proportional to the position of the sleeve.

The sleeve 40 is carried by a rod or pintle 50 to which is attached the lower end of the link 51 in turn pivotally attached at its 40 upper end to the arm 52 on the under side of the butterfly throttle valve 53. By this means, as the throttle valve is opened, the sleeve is raised and as it is raised it opens more of the air tubes 21, 22, 23, 24 and 25 45 as it rises. The butterfly throttle valve 53 is supported on the usual shaft 54 provided on the outside of the carburetor with the operating arm 55. On the lower or inlet end of the mixing chamber is carried the air 50 valve chamber 60, the air pipe 61 provided with the cold air ports 62 projecting from one side thereof and affording an entrance for the greater portion of the air flowing through the carburetor. The air valve is a 55 duplex device. The valve opening 63 is closed by the valve disk 64, hereinafter referred to as the high speed air valve, which seats against and closes the valve opening 63. This valve is perforated by four openings 65 in turn closed by the valve 66, hereinafter called the low speed air valve. Springs 67 and 68 press respectively against the high speed air valve 64 and the low speed air valve 66 and normally tend to hold them 65 against their seats. The pressures of the

springs against their valves are separately regulated by the adjusting screws 70 and 71, respectively, for the low speed and high speed air valves. Detents 72 and 73 respectively hold these screws in adjusted position. It will be observed that the adjusting screw 71 turns on the adjusting screw 70, but it may do so without turning such screw or disturbing the adjustment thereof; on the other hand, turning the adjusting screw 70 on the adjusting screw 71, adjusts the pressure of the spring 67 on the low speed air valve without disturbing the adjustment of the high speed air valve spring. A starting lock 74 operated by an exterior 80 arm 75 may be turned through an angle of approximately 90° so as to hold both valves closed when it is desired to start the engine. Under such circumstances it will be seen that all the air drawn in by the engine will 85 be required to enter through the air tubes 21, etc., as a result of which a large amount of gasoline will be drawn in, and ready starting of the engine will be secured.

Before proceeding to a description of the mode of operation of the device, it is desired to point out that the hot air pipe 80 secured to the pipe 61 may be availed of to close or open the cold air ports 62 more or less as is desired. This is an inexpensive, 95 convenient and efficacious device for controlling the relation of the hot air and cold air supplied to the carburetor.

At low or idling speeds when a small amount of fuel is required by the engine, the high speed air valve 64 will remain permanently closed and the low speed air valve 66 will be open but slightly and subjected to a very slight pressure from its supporting spring so as to afford slight impediment 100 to the opening of the low speed air valve under such conditions. When the engine speed increases and the demand for fuel is increased, then the high speed air valve will be lifted from its seat by the suction and a 105 larger quantity of air proportionate to the increased volume of fuel will be admitted.

At idling speeds with the throttle 53 nearly closed, the sleeve 40 will be at its bottom position and only the air tubes 21 115 and 22 will admit air to the mixing chamber over the gasoline jets 11 and 12, therefore the gasoline will be drawn from only these two jets, a larger amount through the air tube 21 and a smaller amount through the 120 air tube 22, as the port 42 in the sleeve will be only partially open. As the speed of the engine increases with the opening of the throttle 53 the sleeve 40 will be raised. As it is raised it will gradually open the air 125 tubes, permitting additional gasoline jets to deliver gasoline to the air entering through the successive air tubes.

It is to be observed that in starting the engine the locking of the air valves closed 130

- will cause a substantial reduction of pressure in the mixing chamber owing to the suction exerted by the engine cylinders and the air drawn in through the air tubes over the gasolene jets will be drawn in violently and a considerable quantity of gasolene will be inducted into the mixing chamber so as thereby to secure a rich mixture, suitable for starting purposes when the engine is cold.
- 10 When the engine starts the air valves will be unlocked and they will begin to function, thus bringing the apparatus into regular operative condition. Assuming now running conditions and a light load and a low speed,
- 15 the air drawn in through the air tubes will draw in with it gasolene, and as the engine load is increased and the throttle is opened wider, more gasolene is drawn in and with it more air, and so uniform proportions of
- 20 air and gasolene are drawn in at all speeds.
- The air flowing in through the air tubes flows at right angles to the direction in which the gasolene jets discharge their gasolene thereinto, and as the gasolene emerges from the jet orifices the current of air flowing through the air tubes sprays it into a fine mist, atomizer fashion. This fine mist of gasolene and air—this superloaded air—enters the mixing chamber at right angles to the direction of flow of the air which is passing through it, and so it is required to change its direction of movement. Thus, it will be observed, the gasolene particles are taken from the jets in a direction at right angles to the flow at the point of emergence from the jets and introduced into a mixing chamber, and caused a second time to move in a direction at right angles to that at which it entered the chamber, so the gasolene particles are buffeted about and the mixing of the particles of gasolene with the air is efficaciously secured. In addition, owing to the fact that the center of a stream of air flows more rapidly than the exterior portions, particles of gasolene entering the mixing chamber tend to move toward the center of the stream of air, and when so doing they are subjected to a further tendency to be mixed with the stream of air so as to produce a mixture of uniform and homogeneous composition.
- Another feature of the construction which contributes to the homogeneity of the mixture is the arrangement of the successively opening air tubes. The first air tube 21 is located at a certain position in the periphery of the mixing chamber and the second air tube 22 is located nearly opposite the first, so that as the air tubes discharge their mixture of gasolene and air into the mixing chamber they are discharged from opposing points toward each other and upon the stream of air flowing at right angles to them, so that we have, for example, with the throttle wide open, five streams direct-
- ed at the axis of a single stream flowing at right angles to the five, thereby securing an efficient mixture of the gasolene and air. The third air tube is located at an angle to both of the first two, the fourth at an angle to all three, and the fifth at an angle to all of the four, so that when all five streams of air and gasolene are entering the air chamber through the five air tubes, a condition is secured in which five separate radially inwardly directed streams of air and gasolene are projected each against every other stream and all five are directed into a stream of air moving at right angles to them all. Thus is obtained an intimate and homogeneous mixture of the gasolene and air. It has been found in practice to be desirable to regulate the relative areas of the several jets, and in the carburetor of the drawings their diameters are as follows:—
- jet 1, .030"; jet 2, .035"; jet 3, .035"; jet 4, .025"; and jet 5, .020". The total area of the jets is much larger than the total area of the jet or jets used in carburetors supplying as many cubic feet of mixture as is capable of being supplied by this carburetor. While the area orifices of the jets have been increased, the amount of gasolene consumed in making the mixture has been reduced, and, paradoxical as it may appear, the fact remains that the result of increasing the area of the orifices of the jets has been to reduce the gasolene consumption. In a carburetor of the construction of the drawings, having an opening through the gasolene sleeve of an inch and a half in diameter, sufficient gas may be mixed and delivered to a gasolene engine consuming substantially 18,000 cubic feet of mixture per minute.
- The modified form of the invention illustrated in Figs. 6 and 7 is a form adapted for use with gasolene and kerosene. The gasolene float chamber 100 delivers gasolene to the gasolene jet 101 which corresponds in position to the jet 13 in the first described construction, and the kerosene chamber 110 delivers kerosene to the kerosene jets 112, 113, 114 and 115. The gasolene control sleeve 120 is similar to the gasolene control sleeve 40 except that the port for the gasolene jet 101 is a round hole corresponding in size to the air tube of the jet 101, so that after the engine is started the gasolene tube will be cut off by the sleeve 120 by the non-registry of the port corresponding to the gasolene jet 101. If desired, the port in the sleeve 120 for the gasolene jet 101 may be so shaped as to permit the drawing of more or less gasolene vapor into the mixture at all times during running. For example, it might be so shaped as to permit more gasolene to enter with the throttle narrowly closed and gradually less gasolene to enter as the throttle opening

widened. The kerosene jets 112, 113, 114 and 115 open in the order named. It will be observed that the gasolene jet is used for starting and idling and that at wider throttles the kerosene is admitted and the gasolene shut off. The change from gasolene to kerosene is automatically accomplished by opening the throttle, and the construction of Figs. 6 and 7 embodies all the principles of construction of the one-fuel carbureter illustrated in Figs. 1 to 5 inclusive, and, in addition, this double fuel feature.

The present invention is not limited to the illustrated embodiment thereof, as it may be embodied in other forms; thus, for example, more or less air tubes may be employed, the angle of entrance of the air tubes into the mixing chamber may vary, and other arrangements of the parts within the scope of the claims may be used. The words "gasolene" and "kerosene," as used in the foregoing description, are not used in a limited sense but as definitive of fuels suitable for mixture with air to form a combustible mixture for use in internal combustion engines.

Having thus described the invention, what is claimed is:—

1. A carbureter having, in combination, a mixing chamber provided with a gasolene supply and having an inlet at one end and an outlet at the other, the inlet being provided with a high-speed valve and a low-speed valve, and locking means for locking both valves closed for starting.

2. A carbureter having, in combination, an elongated mixing chamber having a main air inlet at one end, a discharge outlet at the other, air openings between its ends, jets in the air openings, and means for supplying the jets with different fuels.

3. A carbureter having, in combination, a mixing chamber provided with a single lateral air opening having a jet in the opening, means for supplying a more readily volatilizable fuel thereto, a plurality of lateral air openings in the chamber each having a jet in the openings, and means for supplying a less readily volatilizable fuel to the jets in the latter openings.

4. A carbureter having, in combination, a mixing chamber provided with a lateral air opening and having a jet in the opening, means for supplying a more readily volatilizable fuel to said jet, another lateral air opening in the chamber having a jet in it, means for furnishing a less readily volatilizable fuel to said last-named jet, and means for controlling the air openings having provision for closing the former air opening with the opening of the latter air opening.

5. A carbureter having, in combination, a mixing chamber provided with a lateral air opening having a gasolene jet in the opening and with a lateral opening having a kerosene jet in the opening, and a sleeve for closing the gasolene jet opening with the opening of the kerosene jet opening.

6. A carbureter having, in combination, a mixing chamber having an air inlet at one end and a discharge outlet at the other end, and provided with lateral air openings each having a gasolene jet, each of said air openings being arranged out of line with all the other air openings.

7. A carbureter having, in combination, a mixing chamber having an air inlet at one end and a discharge outlet at the other end, and provided with lateral air openings, jets in the openings, and means for supplying one kind of fuel to one jet and another kind of fuel to another jet.

8. A carbureter having, in combination, a mixing chamber provided with an air inlet at one end and a discharge outlet at the other end, a source of fuel supply, a pipe leading therefrom encircling the mixing chamber, lateral air openings in the mixing chamber, and jets in the pipe and projecting one each into a lateral air opening.

9. A carbureter having, in combination, a mixing chamber, a source of fuel supply, a pipe leading therefrom and embracing the mixing chamber, jets in the pipe, lateral air openings in the mixing chamber registering one each with the jets, and means for covering and uncovering the lateral openings *seriatim*.

10. A carbureter having, in combination, an elongated mixing chamber having an air inlet at one end and a discharge outlet at the other end, and provided with lateral air openings each having a gasolene jet, a sleeve in the mixing chamber for opening the air openings successively, a throttle-controlled means for regulating the sleeve, and means unconnected with the throttle-controlled means for varying the amount of air admitted to the mixing chamber by the air inlet.
